UNITED STATES PATENT OFFICE.

JOHN F. CAVANAGH, OF PROVIDENCE, RHODE ISLAND, ASSIGNOR TO THE SCREW MACHINE PRODUCTS CORPORATION, OF PROVIDENCE, RHODE ISLAND, A CORPORATION OF RHODE ISLAND.

SELECTIVE TELEPHONE SYSTEM.

Application filed November 24, 1924. Serial No. 751,824.

This invention relates to improvements in selective telephone systems, and has for its object to provide means interposed in the circuit of such a system for controlling the connection between the calling and the selected or called station.

A further object of this invention is to provide such a system in which the functions of both a selective signalling and a central control systems are combined.

A still further object of this invention is to interpose in the signal circuit a central station having a control element, whereby the central station must be called before connection can be completed to the selected station, and whereby the controlling element may be operated to permit a selected station to be called directly from the calling station.

This invention further consists in the provision of a unit adapted to be interposed in a selective signal circuit to permit one of the stations of the selective systems to serve as a central control station when desired.

The invention further consists in so constructing this central control unit that it may be readily attached to a telephone set.

With these and other objects in view, the invention consists of certain novel features of construction, as will be more fully described, and particularly pointed out in the appended claims.

In the accompanying drawings:

Figure 1 is a perspective view of a telephone desk instrument having a selecting dial and a central control unit.

Figure 2 is a perspective view showing a fragmental portion of the detachable base of the desk instrument, illustrating the central control unit as mounted therein with a manually-operable contact closing member.

Figure 3 is a sectional elevation illustrating my improved central control unit as attached to the base of the usual desk instrument.

Figure 4 is a plan view of my central controlling unit as removed from the base of the desk instrument.

Figure 5 is a side elevation of the contact-closing button member disconnected from its frame and showing it rotated into retracted position.

Figure 6 is the same as Figure 5 but illustrating the button member as rotated into extended position.

Figure 7 is a sectional elevation of the contact-closing button member, illustrating the general construction of the same.

Figure 8 is a schematic diagram illustrating the wiring connections to the different stations and instruments of my improved selective telephone system.

In the practical operation of private telephone systems such for instance as those employed in schools, hospitals, and various private institutions, it is found of advantage to provide means whereby control of the use of the system between stations, may be exercised by some person in authority, and in the absence of such person the system may, if desired, be caused to function as a selective system for any desired period at which time any station may call any other station without an act on the part of the operator at the central station.

Another advantageous feature of my improved telephoning system is that the central control station operator is not called upon to do the signalling for the calling party but merely has to sanction the call by closing a relay to make a connection, whereupon the one calling may signal directly to the called station thus requiring the expenditure of but the minimum amount of time by the central operator. Then again by my improved system the central control circuit when temporarily set is automatically restored to its original condition at the end of each talking period; and the following is a detailed description of the present embodiment of my invention showing one system of wiring and arrangement of parts by which these advantageous results may be accomplished:

This invention, as herein described, is applied to an automatic telephone system of the common talking type having a multiplicity of telephone stations, and Figure 8 of the drawings illustrates the wiring diagram of three of such stations indicated as stations 1, 2, and 3. The wiring diagrams of stations 2 and 3 illustrate the circuit connections to a telephone station of the ordinary type, each of which has a rotatable dial by which one of the other different stations in the system may be connected and signalled, while station 1 of my improved system is similarly wired and in addition, is provided with a central control unit 10 of the type best illustrated in Figures 2, 3, and 4. The mechanism of the cen-

tral control unit is shown as mounted upon a base plate 11 which is provided with an annular flange 12 adapted to set inside of the lower rolled edge 13 of the base 14 of a portable desk instrument 15 and is adapted to be secured in position on the base of the instrument by means of a screw 16 threaded into the post 17.

On the base plate 11 are mounted flexible spring contacts 22 commonly known in the trade as a "build up" which contacts are connected to the usual selecting switchboard or selecting unit by means of wires 23 and 25 through binding screws 24. These spring contact members, as illustrated in Figure 8, are arranged to normally cause the pair of contacts 107 to be separated to interrupt the ringing circuit between the selecting and the selected stations and the pair of contacts 101 to be in engagement to connect the ringing circuit of the selecting station with that of the central station. In order that the ringing circuit to the selected station may be closed and that to the central station opened by an operator at the central station sanctioning the call an armature 19 having an arm 21 is pivoted at 20 on the yoke 26, which is supported on a bracket 27 fastened to the base plate 11, and is operated by push button 29 through a yielding presser member 31. This button is slidably mounted in a tubular member 28 threaded into the flange 12 of the base member, and normally held in withdrawn position by spring 32 acting between the button 29 and the bridge member 31a. An inward pressure on the button 29 serves to swing the armature 19 with its arm 21 to move contacts 107, see Figure 8, into engagement and at the same time separate the pair of contacts 58 and the pair of contacts 101, and in order to retain these contacts in this position to which they have been moved during the talking period an electromagnet 18 is provided which is energized upon movement of these contacts to hold armature 19 in its operating position, thus it is only necessary for the central operator when desiring to sanction the call, to press the button 29 to connect the ringing circuit of the calling station with that of the selected station, which connection is automatically maintained by this magnet 18 until all the ear phones in the circuit are placed in inoperative position on their respective hooks thus shutting off the current flowing thru the lines. However, when the central operator desires to be temporarily absent the circuit may be returned to selective service by causing the armature 19 to remain in call-sanctioned position. This is done by merely turning the button 29 to the right which causes the pin 33 in the end 30 of the button 29 to ride on the face of the cam 34 formed on the end of the tubular member 28

and advance the pressed member 31 into engagement with the armature 19, the pin entering a recess 35, see Figure 6, in the edge of the cam which causes it to remain in this position thus connecting the circuit of the stations to operate as a selective service for a prolonged period, or until the button 29 is manually moved to withdrawn position.

With reference to the wiring diagram of Figure 8, in the operation of calling from station 2 to station 3 the dial 36 at station 2 (now the calling station), is rotated into position so that the designation corresponding to station 3 is under the pointer 46. The receiver 37 is then removed from its hook 38, which act opens hook switch contacts 39 and closes hook switch contacts 40, which closing completes the circuit to the connecting magnet 41 drawing up armature 42, causing detent pawl 43 to move into operating relationship with the rack segment 44 against action of spring 45. The electrical circuit which causes the action of this mechanism may be traced from battery 47 through wires 48 and 49 to contact points 40, through transmitter 50, induction coil primary 51, wire 52 to terminal 53, wire 54, through relay 55, wires 56 and 57 through central control contacts 58, wire 59, jack 60, wire 61, connecting magnet 41, wire 62, jack 63, wire 64 to battery 47.

Through the act of lifting the receiver 37 the dial mechanism is mechanically released which in returning to normal, intermittently closes the contacts 65 a number of times corresponding to the number of the station selected, which in this case is station 3. Therefore, the necessary number of impulses will be transmitted to the selecting magnet 66 to cause the armature 67 to be operated the required number of times to rotate the wiper arm 68 step by step, to engage the contact designated as 3, which position of the wiper arm 68 is indicated by dotted lines. These transmitted impulses to the magnet 66 from contacts 65 may be traced on the wiring diagram of Figure 8 as follows: From the plus side of battery 47 through wires 48 and 49, through hook switch contacts 40, wire 69, jack 70, interrupter contacts 65, jack 71, wires 72 and 73 to terminal 74, wire 75 through contacts 76 which were closed by armature 77 when the relay 55 was energized through the act of lifting the receiver from its hook, thence through wires 78 and 79, jack 80, wire 81, selecting magnet 66 back through wire 82, jack 63, wire 64 to the minus side of battery 47.

Assuming that the central control contacts and relay are in the position shown in Figure 8, the next act at the calling station is to press the push button 83 in the base of the instrument thus ringing a bell 84 at station 1, which is herein shown as being connected to perform the function of central control sta-

tion. The operation of pressing this button 83 shunts the primary of the induction coil at the calling station, in this case station 2, to increase the current flow through connecting magnet 41 which draws up auxiliary armature 86 to close contacts 85 which completes the circuit to bell 84. The ringing circuit may be traced on the wiring diagram of Figure 8 from the plus side of battery 47 through wires 48, and 49, contacts 40, wire 69, jack 70, contacts 87, wire 88, jack 89, button contacts 90, wires 91 and 92, terminal 53, wire 54, through relay 55 to wire 56 down through wire 57, contacts 58, wire 59, jack 60, wire 61, connecting magnet 41 which draws up armature 86 to close contacts 85, back through wire 62, through jack 63, wire 64 to the minus side of battery 47. The closing of contacts 85 shunts the current to bell 84, which may be traced in the following manner:—Taking the current from wire 56, previously traced and shown to be conducting current upon the pushing of button 83, it is conducted through relay 93, wire 94 to terminal 95, through bell 84, wire 96, hook switch contacts 97, wire 98, terminal 99, wire 100, through contacts 101, wire 102, jack 103, wire 104, contacts 85, wires 105 and 81, through selecting magnet 66, wire 82, jack 63, wire 64, back to the minus side of battery 47.

It will be seen that instead of ringing the bell of the selected station directly (here station 3) the central station is notified by the ringing of its bell. If now central station 33 sanctions the call, button 29 of central control unit is pushed inwardly, and as current is flowing through wires 56, and 57, contacts 58 and wire 59, the opening of contacts 58 by the pushing of button 29 shunts the current along 40 wire 105, through magnet 10, wire 106, back to wire 59 energizing magnet 10 to hold armature 19 in operating position. The drawing up of the armature separates the contacts at 58 and at 101 and closes contacts 107. The 45 calling station #2 may now signal the called station #3, directly. In other words, the ringing circuit of station 2 is directly connected to the ringing circuit of station 3, whereby now the bell 108 may be rung by 50 operating push button 83, which circuit is traced on the wiring diagram as follows: The pressing of the button closes contacts 85 as pointed out above and the current of the circuit thus completed is traced by taking the 55 current received from wire 56 which passes through relay 109, wire 110, terminal 111, bell 108 through hook switch contacts 112 back to wire 113, terminal 114, wire 115, to #3 contact point of the selector through wiper arm 60 68, brush 116, wire 117, jack 118, wire 119, central control unit contacts 107, wire 102, jack 103, contacts 85, wire 81, selecting magnets 66, wire 82, jack 63, wire 64 to the minus side of battery 47. This circuit energized by 65 the pressing of button 83 serves to ring the

bell 108 of station 3, which ringing calls that station after which the conversation between these two stations may take place. Upon the completing of which conversation and the hanging up of the receivers upon their respective hooks, the connecting magnet 41 is de-energized and the retaining pawl 43 is caused to release its segment permitting it to return to normal under action of spring 45 and open the circuit to all of the stations and at the same time magnet 10 is deenergized releasing armature 19 and restoring its contact points to normal. 70 75

From the above it will be seen, that a ringing circuit to a selected station is completed only when the armature 19 is pressed downwardly against the magnet 10, and when the operator desires to leave the central station for a prolonged stay it is only necessary to rotate the presser button 29 which locks the armature 19 in operative position thus permitting the calls from any station to pass directly to the called station independently of any action at the central station. 80 85

The foregoing description is directed solely 90 towards the construction illustrated, but I desire it to be understood that I reserve the privilege of resorting to all the mechanical changes to which the device is susceptible, the invention being defined and limited only by 95 the terms of the appended claims.

I claim:

1. In a selective telephone system, a plurality of stations, means for connecting said stations in circuit, an automatic selecting switchboard for partially completing the connection between said stations, controlling means interposed in said connecting means at one of said stations for connecting that station to be called before the connection between any two other stations can be completed, and manually operable means for completing the connection between said two other stations. 100 105

2. In a selective telephone system, a plurality of stations, means for connecting said stations in circuit including a signal circuit, an automatic selecting switchboard for completing the connection between said stations, a central station, means for normally connecting said central station to be first called by a user, and means at said central station for connecting the signal circuit so that a selected station may then be called. 110 115

3. In a selective telephone system, a plurality of stations, means for connecting said stations in circuit including a signal circuit, an automatic selecting switchboard in said circuit for completing the connection between said stations, a central station in said circuit normally connected to be called by a user of one of the other stations, manually operable means at said central station for connecting the signal circuit so that a selected station may be called directly by the user of one of 120 125 130

the other stations, and electro-magnetic means for maintaining the circuit closed during each talking period.

4. In a selective telephone system, a plurality of stations, means for connecting said stations in circuit, an automatic selecting switchboard in said circuit for completing the connection between said stations, a central station in said circuit, a ringing circuit normally connected to said central station and disconnected from the other stations, and manually operable means at the central station for opening that circuit to said central station and connecting the same to the called station, and means at the calling station for ringing the previously selected station directly by the user.

5. In a selective telephone system, a plurality of stations, means for connecting said stations in circuit, a selecting switchboard for completing the connection between said stations, a central station, a signal circuit normally closed thereto and open to the other stations, manually operable means at the central station for opening that circuit to said central station and connecting the signal circuit so that any other previously selected station may be called by the user, and electrical means for maintaining the circuit closed during each talking period.

6. In a selective telephone system, a plurality of stations, including a central station normally connected to be called from any other of said stations, means at each station for completing a signal circuit therefrom, and manually operable means at the central station for breaking the signal circuit and connecting it in the signal circuit of a previously selected station.

49 7. In a selective telephone system, a plurality of stations, including a central station normally connected to be called from any other of said stations, means at each station for completing a signal circuit therefrom, and manually operable means at the central station for breaking the signal circuit thereto and connecting it in the signal circuit of a previously selected station, and electrical means for maintaining this circuit closed during each talking period.

8. In a selective telephone system having a plurality of stations, a central station, means at the calling station for selecting the signal circuit of called stations, means interposed in said signal circuit between the different stations by which the signal circuit of the central station is normally connected with the calling stations, and manually operable means for connecting the signal circuit of the calling and called stations and disconnecting the signal circuit to the central station.

60 9. In a selective telephone system having a plurality of stations, manually operable means at each station for operating a selec-

70 tor to connect the talking and signalling circuits of the calling and called stations and switch means interposed in the selected signal circuit to disconnect that circuit and to normally connect the calling station in the signal circuit with a central station, and manually operable means to operate said switch means to connect said selected signal circuit and disconnect the signal circuit of said central station.

75 10. In a selective telephone system, a plurality of stations including a central station, each station having a transmitter, a receiver, a signal device and station-selecting mechanism, a signal switch at each station, said central station being normally connected to be signalled from all other stations, and a manually-operable switch at the central station for simultaneously disconnecting that station signal from all other stations and connecting the calling station to its selected station.

80 11. In a selective telephone system, a plurality of stations including a central station, a selective switchboard, a station controlled automatic selector, a manually-controlled switch normally connected to complete the signal circuit through said switchboard from the selecting station to the central station only and responsive to manual manipulation to disconnect the signal circuit from said central station and connect it to the signal circuit of said selected station through said switch and said automatic selector.

85 12. In a selective telephone system having a plurality of stations connected through a selecting switchboard, a central station, means operable at the calling station for selecting the signal circuit of the called station, switch means interposed in the selected signal circuit for normally opening that circuit and closing the signal circuit of the central station, electro magnetic means for holding said switch means to close the selected signal circuit and open the central signal circuit, and manually operable means for closing said selected signal circuit and operating said electro magnetic means.

90 13. In a selective telephone system having a plurality of stations connected in the circuit including a central station, means in the system whereby the central station is first called by the user, a portable desk instrument at the central station, and means carried by said instrument responsive to a manual operation for connecting the signal circuit so that a selected station may be called directly by the user from the calling station.

120 14. In a selective telephone system having a plurality of stations connected in the circuit including a central station, means in the system whereby the central station is first called by the user, a portable desk instrument at the central station having a removable base member, and means carried in said base mem-

ber responsive to manual operation for connecting the signal circuit so that a selected station may be called directly by the user.

15. In a selective telephone system having 5 a plurality of stations including a central station connected through an automatic selecting switchboard, a portable desk instrument in the system at the central station, a base member carried by said instrument, and controlling means carried by said base member by which the signal circuit to central may be opened and connection made whereby the selected station may be called directly by the user.
- 15 16. In a selective telephone system having a plurality of stations including a central station connected through an automatic selecting switchboard, a portable desk instrument in the system at the central station, a 10 base member carried by said instrument, controlling means carried by said base member

by which the signal circuit to central may be opened and connection made whereby the selected station may be called directly by the user, and means in said controlling means 25 whereby said connection may be automatically broken at the end of each talking period.

17. In a selective telephone system having a plurality of stations including a central station connected through an automatic selecting switchboard, a portable desk instrument in the system at the central station, a base member carried by said instrument, and controlling means carried by said base member by which the signal circuit to central may be 30 opened and connection made whereby the selected station may be called directly by the user, and manually operable means in said controlling means, whereby said connection may be prolonged for any desired period. 35

In testimony whereof I affix my signature.
JOHN F. CAVANAGH.
